UNITED STATES PATENT OFFICE.

HARRY A. CONNERS, OF CINCINNATI, OHIO.

REGULATOR FOR VAPOR HEATING SYSTEMS.

Application filed September 11, 1919. Serial No. 323,104.

To all whom it may concern:

Be it known that I, HARRY A. CONNERS, a citizen of the United States of America, and a resident of Cincinnati, in the county of Hamilton and State of Ohio, have invented a new and useful Improvement in Regulators for Vapor Heating Systems, of which the following is a specification.

My invention relates to a float actuated means for regulating the damper and the draft of furnaces of vapor systems.

One of the disadvantages of these float actuated regulators now in use is that under certain abnormal conditions the water in the system will boil over or escape through the housing of the float.

An object of my invention is an automatic means for preventing water escaping at the float.

Another object of my invention is a positive means for actuating the draft and the damper from the float.

These and other objects are attained by the means described in the specification and illustrated in the accompanying drawings in which:

Fig. 1, is a perspective view of a furnace showing the method of installing the regulator embodying my invention.

Fig. 2, is a cross sectional view of my regulator taken upon the line 2—2 of Fig. 3.

Fig. 3, is a plan view of a portion of the cover on my regulator, showing the cross arm and means for adjusting it.

Fig. 4, is a fragmental view of the upper portion of the housing showing a sectional view of a cup valve.

Fig. 5, is a perspective view of the metal mounting on the gauge.

Fig. 6, is a detail of an attachment for adjusting the cross arm.

Fig. 7, is a fragmental perspective view of a detail of the cross-arm and a sleeve supporting same.

My invention relates to a heat regulator for use on furnaces, comprising a housing A, inclosing a float C which is actuated by the water in the furnace boiler P, contained within the furnace housing P¹, the float in turn actuating a lever K and a cross-arm by means of which the draft or fuel supply on the furnace is regulated, thereby maintaining a certain pressure.

Referring to the drawings.

My regulator comprises a housing A with its cover a, which are made air and water

tight by the fibrous lining a' between them. Mounted in the cover is the valve casing B whose upper portion b is threaded externally and has three apertures g', g², g³, extending vertically thru the top into the hollow central cylindrical portion b' of the valve casing. The holes g', g², are relatively smaller than g³. g', g² are air outlets and are the means of liberating the air from the interior of housing A which is forced into the housing by way of the pipe f' when steam is admitted to the radiator. The air which accumulates in the radiator of the heating system is forced out of the radiator and thru the pipe f' by the steam. The escape of the steam from the radiator is precluded by various valves mounted on the radiator and which practice is common in the art. The lower portion b² of valve casing B is shaped in the form of a semi-spherical body having a ground beveled edge b³ located interiorly of it and forming a seat for valve D.

Valve stem d² slides loosely in the aperture g³ in the valve casing and has fastened to its lower end a valve D whose beveled edge d seats on the edge b³ making an air and water tight joint when seated.

A small rod c fastened to the base of valve D connects the valve with float C, the small rod being fastened in the upper portion of float C. Any movement of the float vertically, would move the valve, this in turn giving movement to the valve stem d² which is the means of actuating the cross-arm and lever as will be explained hereafter.

The housing is connected to the boiler of the furnace by pipe F which is inserted at the base of the housing. An air return pipe f' having the check valve f, is inserted in the upper part of the housing. This check valve is inserted for reasons that will hereinafter be described.

The sleeve G is located above the cover and valve casing and is slidably mounted upon the cross arm H, and the valve stem d² extends slidably through the sleeve. The whole upper portion of the valve stem d² is threaded and two lock-nuts d³ are placed upon it. By having the lock-nuts at the upper extremities of valve stem d², the position of the float is regulated in accordance with the pressure desired in the system.

The cross arm is pivotally mounted on a vertically adjustable bracket h and slides loosely thru a slot g in G and is controlled by the bolt h'. In order that the cross-arm

H may have a reciprocating motion in relation to the sleeve G, due to the fact that it is hinged on *h* and has a vertical movement imparted to it by sleeve G, it is provided with 5 an elongated slot *h*² extending longitudinally of itself. The pivotal mounting of the cross arm is accomplished by having the end of the cross-arm H on which is fastened the chain *n*, weighted, which tends to move the 10 cross-arm upward at G, its upward movement being limited by the two lock-nuts *d*² and the weight of float C.

The chain *n* is fastened at its lower end to lever K, which runs parallel with the furnace and is supported midway by the support *k* which is mounted in the top of the furnace. Chain *m* is fastened at its upper end to lever K, being a continuation of chain *n*. Its lower extremity is fastened to 20 the hinged draft door Y which is of sufficient weight to retain the sleeve in normal engagement with the lock nuts. Fastened to the other end of lever K is the chain *m'*, connecting the flue check draft and lever K, 25 mounted on housing A is a gauge consisting of the metal mounting E, two rods *e*' which pass thru the perforations *e*² in the mounting and are held in place by the collars *e*³. The rods serve to keep the mounting stationary. A glass tube *e* is connected up in 30 the usual way with the casing A. Mounting E is graduated, as shown in Fig. 5, the line *e*⁴ indicating the water line at normal. This gauge indicates the pressure that is being 35 produced.

Plate H² in Fig. 6, is a means for adjusting the cross-arm H to any desired position, for installation of the regulator.

The chains *n*, *m* and *m'* are connected as 40 heretofore explained, of use on furnaces where coal is used as a fuel. On a gas furnace the lever K together with the chain *m'* would be eliminated, and the chain *n* would be continued down to the gas supply 45 turning it off or on in the usual manner.

In operation, when the pressure in the 50 system is increased the water in the casing rises, pushing up on the float which in turn permits the arm H² to be moved upon the pivot *h* because of the weight of the door Y wherefore the lever K is actuated and the door Y closes, and the check draft is opened, thereby decreasing the flame and causing the pressure to decrease when the float would 55 drop again causing the draft to be opened again.

The float C is made of a weight sufficient 60 to counter-balance the weight of the door Y and the chains operating between the cross-arm, the lever K and the check draft and the draft doors. It will therefore be apparent that normally when there is no pressure within the heating system, the weight of the float C will be sufficient to retain the cross-arm and the lever K in such position that

normally the draft door Y is opened and that the check draft is closed. The raising of the float C serves merely to permit the weight of the draft door Y to close the draft door and open the check draft. 70

Should the movement of the draft door Y be impeded by any abnormal condition such as cinders becoming lodged thereunder, or the chains becoming twisted or broken, and the continued heat of the fire, should raise 75 the water in the system above its normal degree, this would carry the float forward and close the valve D against the seat *b*². This would prevent the water of the system from escaping through the holes in the top of the 80 casing.

The check valve *f* prevents any air being drawn into the system when the pressure thereof falls, and when the pressure rises permits air from the heating system to escape out thru holes *g*' and *g*. 85

Having thus described my invention, what I claim is:—

1. In a draft and damper regulator, the combination of a furnace, a boiler associated 90 with the furnace, a housing, a pipe adapted to connect the bottom of the housing with the boiler, a cross arm pivoted to the top of the housing, a lever adapted to be pivoted to the top of the furnace, the furnace being provided with draft and damper doors, cables adapted to connect the opposite ends of the lever with the draft and with the damper door, a float within the housing, a stem carried by the float, means for connecting the 100 stem and the cross arm and for permitting relative movement between the stem and cross arm longitudinally of one another, and a cable connecting the cross arm and the lever. 105

2. In a draft and damper regulator the combination of a furnace, a boiler associated with the furnace, a housing, a pipe adapted to connect the housing to the boiler, a cross arm pivoted upon the top of the 110 housing, a lever adapted to be mounted upon the top of the furnace, the furnace being provided with draft and damper doors, cables adapted to connect the opposite ends of the lever and the furnace doors, a cable connecting one end of the cross arm with one end of the lever, a float in the housing, a valve casing in the top of the housing and having a valve seat, a stem carried by the float and extending thru the valve casing, 115 means for connecting the stem and the cross arm and for permitting relative movement of the stem and cross arm longitudinally of one another, and a valve mounted upon the stem and adapted to engage the valve seat on the valve casing. 120

3. In a regulator of the class described the combination of a housing, a valve casing mounted in the top of the housing having apertures in its top and a valve seat 125 130

- at its base, a float in the housing, a stem carried by the float extending thru an aperture in the casing, a valve carried by the stem adapted to engage the valve seat, a 65
- 5 pivotally mounted cross arm and means for connecting the cross arm and the stem and for permitting movement of the stem relative to the cross arm for closing the valve.
- 10 4. In a heating system of the class described the combination of a furnace, a boiler associated with the furnace adapted to supply energy to the heating system, a housing communicating at its bottom with the boiler, an air return pipe communicating with the system and with the top of the housing adapted to discharge air from the system into the housing, a check valve adapted to preclude the passage of air from 70
- 15 the housing into the air return pipe, a valve casing mounted in the top of the housing and having apertures in its top, a valve stem extending thru one of the apertures in the casing, a float in the housing carried 75
- 20 by the valve stem, a valve carried by the stem controlling communication between the apertures in the casing top and the interior of the housing, a pivotally mounted cross arm above the housing, the cross arm having an elongated slot formed in it, a sleeve slidably mounted upon the valve stem, means limiting the movement of the sleeve from the valve stem, a bolt carried by the sleeve extending slidably thru the 80
- 25 elongated slot in the cross arm, and means connected with the cross arm for controlling the fire in the furnace. 85
- 30 5. In a regulator of the class described the combination of a housing, a valve casing at the top of the housing having apertures in its top, a valve stem extending reciprocally thru one of the apertures in the valve casing, a valve and a float carried by the valve stem, the valve controlling communication of the apertures in the casing and the interior of the housing, a sleeve reciprocally mounted upon the valve stem exteriorly to the housing, means limiting the movement of the sleeve upon the valve stem, 90
- 35 and a pivotally mounted cross arm having a sliding pivotal connection with the sleeve. 95
- 40 6. A regulating device for heating systems of the class described comprising a housing having apertures in its top, a valve stem extending thru one of the apertures, a float mounted on the valve stem contained within the housing, a valve carried by the valve stem controlling communication between the apertures in the top of the housing and the interior of the housing, a sleeve reciprocally mounted upon the stem exteriorly of the housing, means limiting the 100
- 45 movement at which the sleeve may be moved away from the float, and a pivotally mounted cross arm having a sliding pivotal connection with the sleeve. 105
- 50 7. A regulating device for heating systems of the class described comprising a housing having apertures in its top, a valve stem extending thru one of the apertures, a float mounted on the valve stem and contained within the housing, a valve carried by the valve stem controlling communication between the apertures in the top of the housing and the interior of the housing, a sleeve reciprocally mounted upon the stem exteriorly to the housing, means limiting the movement at which the sleeve may be moved away from the float, a pivotally mounted cross arm having a sliding pivotal connection with the sleeve, a return pipe 110
- 55 adapted to communicate with the interior of the housing, and a check valve adapted to permit drainage from the return pipe into the housing. 115
- 60 8. In a device of the class described the combination of a housing having perforations in its top adapted to communicate with the inside of the housing, a valve stem reciprocally extending through one of the perforations in the top of the housing, a float in the housing carried by the valve stem, a valve carried by the valve stem controlling communication between the perforations and the housing, and a cross bar pivotally mounted externally to the housing and having a sliding pivoted connection with the valve stem whereby the valve stem may have a limited independent movement. 120
- 65 9. In a device of the class described the combination of a housing having perforations in its top adapted to communicate with the inside of the housing, a valve stem extending reciprocally through one of the perforations, a float on the valve stem, contained within the housing, a valve on the valve stem controlling communication between the perforations and the housing, a sleeve reciprocally mounted on the valve stem exteriorly to the housing, means limiting the movement of the sleeve away from the float, and a cross bar connected to the sleeve, the parts bearing a relation such that the valve stem may have movement independent of the cross bar for seating the valve, and that on movement of the valve stem in the opposite direction, the movement of the valve stem is imparted to the cross bar. 125
- 70 In testimony whereof, I have hereunto 120
- 75 subscribed my name this 6th day of September, 1919.

HARRY A. CONNERS.
